(57) **CLAIM**

The ornamental design for a medical test instrument, as shown and described.

DESCRIPTION

FIG. 1 is a front view of a medical test instrument showing a first embodiment of the claimed design;

FIG. 2 is a back view thereof;

FIG. 3 is a bottom view thereof;

FIG. 4 is a top view thereof;

FIG. 5 is a left side view thereof;

FIG. 6 is a right side view thereof;

FIG. 7 is a top front perspective view thereof;

FIG. 8 is a bottom back perspective view thereof;

FIG. 9 is a front view of a medical test instrument showing a second embodiment of the claimed design;

FIG. 10 is a back view thereof;

FIG. 11 is a bottom view thereof;

FIG. 12 is a top view thereof;

FIG. 13 is a left side view thereof;

FIG. 14 is a right side view thereof; and,

FIG. 15 is a top front perspective view thereof.

The dotted lines in the drawings depict portions of the medical test instrument that form no part of the claimed design.
